CLAIM

We claim the ornamental design for a razor handle, as shown and described.

DESCRIPTION

This application is a continuation of and claims priority to U.S. design patent Ser. No. 29/655,193 filed on 29 Jun. 2018 and U.S. design patent Ser. No. 29/639,847 filed on 9 Mar. 2018 the entirety is hereby incorporated by reference.

FIG. 1 is a front perspective of a razor handle according to an embodiment of our new design;

FIG. 2 is a left elevational view of a razor handle according to an embodiment of our new design;

FIG. 3 is a right elevational view of a razor handle according to an embodiment of our new design;

FIG. 4 is a top plan view of a razor handle according to an embodiment of our new design;

FIG. 5 is a bottom plan view of a razor handle according to an embodiment of our new design;

FIG. 6 is a front elevational view of a razor handle according to an embodiment of our new design; and,

FIG. 7 is a rear elevational view of a razor handle according to an embodiment of our new design.

The broken lines illustrate a button, handle end, and docking features and form no part the claimed design.

1 Claim, 7 Drawing Sheets
